C. E. STRYKER

ADJUSTABLE RESISTANCE UNIT

Filed Oct. 21, 1925

Inventor

Clinton E. Stryker
Williams, Bradbury,
Mc Caleb & Hinkle Atty.

UNITED STATES PATENT OFFICE.

CLINTON E. STRYKER, OF NORTH CHICAGO, ILLINOIS, ASSIGNOR TO FANSTEEL PRODUCTS COMPANY, INC., OF NORTH CHICAGO, ILLINOIS, A CORPORATION OF NEW YORK.

ADJUSTABLE RESISTANCE UNIT.

Application filed October 21, 1925. Serial No. 63,832.

My invention relates to adjustable electrical resistance devices such as those used in railway battery and signal circuits, and generally in electrical circuits where an adjustable resistance is required, where the 5 adjustments are to be maintained for a considerable period of time, and where devices may be subject to jars and vibrations.

The object of my invention is to provide 10 an adjustable resistance unit with a small number of parts, which is simple in construction and can be cheaply manufactured.

A further object is to provide a resistance 15 device in which adjustment of the resistance may be quickly and easily made.

A further object is to provide an adjustable resistance unit which is adapted to be readily inserted and removed from an electrical circuit.

20 A further object is to provide a comparatively rigid support for an adjustable contact so that relatively great pressure may be exerted to firmly hold the contact member against the resistance wire.

25 A further object is to provide an improved contact element which is easily made and assembled.

Other objects will appear from the following 30 description, reference being made to the accompanying drawings in which:

Fig. 1 is an end elevation of the improved resistance device.

Fig. 2 is a longitudinal vertical sectional view of the device taken on the line 2—2 35 of Fig. 4, also showing how the same may be suitably connected to a panel board.

Fig. 3 is a transverse vertical sectional view of the device taken on the line 3—3 of Fig. 4.

40 Fig. 4 is a plan view of the device.

The block or body portion 1 of the resistance device is keystone shaped so as to be easily molded of porcelain or any other suitable insulating material. It has suitable pedestals 2 which are slotted as at 3 to provide 45 passages for the resistance wire 4. The block is grooved on three sides to receive the resistance wire 4 which is wound around the block in the usual manner. These grooves 50 are so formed that the contacting portions of the wire lie transversely of the block on its top or contacting surface which is not grooved. The open slotted support bracket 5 fits into a formed depression in the end of

the block to prevent it from turning, and is 55 secured by the screw 6 which lies in a hole formed in the block, the hole being enlarged for a short distance as shown at 7 to receive the head of the screw 6.

In the process of assembly the bracket 5 60 is secured to the block 1, the resistance wire attached to this bracket and then wound on the block, and the loose end passed through the slot 3 (shown at the right in Figure 2) and wound around the pedestal 2 to prevent 65 it from unwinding while the remaining assembly operations are being performed. Thus the pedestal 2 with the slot 3 greatly facilitates the assembly by providing a means upon which the loose end of the wire 70 may be temporarily anchored during the assembly operation.

The contact support 8 is substantially inverted U-shaped and is integral with the other support bracket 8^A. The contact support is bridged over the block, fits into depressions formed in the ends of the block and is secured to the block by means of the flat headed machine screw 9 which extends 75 through the block and at its end is threaded 80 into the downwardly bent portion of the contact support, thus rigidly fastening it in place. The bridge portion has a full length longitudinal slot 8^B.

The contact member 10 comprises a strip 85 of slightly resilient conducting material bent so as to have two U-shaped contacting surfaces and is loosely riveted at its center to the thumb screw 11 which extends through and is slidable in the slot 8^B. The contacting 90 surfaces of the member 10 are wide enough to embrace a number of convolutions of the resistance wire as shown in Figure 2, thereby securing a plurality of points of contact to insure good electrical connection with the 95 resistance wire. The contact member 10 has upwardly projecting ends 10^A which extend through suitable slots in the guide 12. These ends by their engagement with the sides of the contact support 8 maintain the contact 100 member in substantially transverse position. The screw 11 is fitted with a suitable thumb nut 13 by means of which the contact member may be clamped in the desired adjusted 105 position along the contact support 8. The resistance wire is suitably connected, preferably soldered, at one end to the bracket 5 and at the other to the bracket 8^A. It will

be seen that by moving the contact member to the right (Figs. 2 and 4) the resistance in the circuit may be increased while by moving it to the left the resistance may be 5 decreased.

The resistance unit may be secured to panel board or other suitable support 14 by means of the screws 15 and the nuts 16, 17. The wire connections to the unit are made in 10 the usual manner by tightening the thumb screws 18 over the connecting wires. Due to the disposition of the open end slots in the support brackets 5 and 8^A, the unit may be detached from the panel by merely loosening the thumb screws 18 and the nuts 17. 15

The invention is capable of variation and adaptation in many respects for use in different embodiments without departure from the principles of the invention.

20 I do not restrict myself in unessential particulars but what I claim and desire to secure by Letters Patent is:

1. A resistance unit comprising an insulating block provided with vertical depressions in each end, a resistance wire wound thereon, a metal strip extending outwardly at the base to form a supporting bracket, bent upwardly to fit in one of said vertical depressions, bent horizontally and slotted to 25 form a support for a contact member and bent downwardly to fit in the other of said vertical depressions, a resilient contact mem- 30

ber and means for holding it in a fixed position, and means passing through said block and engaging the upwardly and downwardly 35 extending portions of the metal strip to prevent the block from turning on the bracket and to rigidly hold the contact supporting member.

2. A resistance unit comprising an insulating block provided with vertical depressions in each end, a resistance wire wound on said block, a single metal strip adapted to serve as a bracket support for the block, to fit in the depressions to prevent rotation of the block, and to form a contact support bridging said block, said contact support being slotted horizontally, a contact member comprising a thumb screw, a slotted guide and resilient conducting material, the latter being secured to the thumb screw, bent downwardly on each side of the screw to contact with the wire and then bent upwardly through the slots in the slotted guide to engage said contact support whereby the ends of the resilient member, the slotted guides and the contact support maintain themselves in fixed relative position, and means passing through the metal strip and the insulating block for rigidly holding 55 these elements in position. 60

In witness whereof, I hereunto subscribe my name this 9th day of October, 1925.

C. E. STRYKER.
